(57) **CLAIM**

The ornamental design for a bottle cap, as shown and described.

DESCRIPTION

FIG. 1 is a top, front, and right perspective view of a bottle cap in accordance with the present design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, front, and left perspective view of the bottle cap of FIG. 1 wherein the lid is open and the handle is rotated backward;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a top, front, and right perspective view of the bottle cap of FIG. 1 wherein the lid is open and the handle is rotated backward; and,

FIG. 16 is a bottom, front, and right perspective view of the bottle cap of FIG. 1 wherein the lid is open and the handle is rotated backward.

The broken lines shown in the drawings illustrate portions of the bottle, the bottle cap, and/or the bottle sleeve that form no part of the claimed design. The broken lines in the views of FIGS. 1-7 showing a bottle and bottle sleeve, or showing portions of a bottle and bottle sleeve, form no part of the claimed design. The broken lines in FIGS. 1-6 and 8-16 that depict portions of the bottle cap form no part of the claimed design.

1 Claim, 10 Drawing Sheets
